JP D 12,010

Design No. 12,010, dated November 2, 1880.

UNITED STATES PATENT OFFICE.

EDUARD LEISSNER, OF NEW YORK, N. Y., ASSIGNOR TO LEISSNER & LOUIS,
OF SAME PLACE.

DESIGN FOR WALL-PAPER.

SPECIFICATION forming part of Design No. 12,010, dated November 2, 1880.

Application filed July 31, 1880. Term of patent 3½ years.

To all whom it may concern:

Be it known that I, EDUARD LEISSNER, of New York, in the county and State of New York, have invented a new and original Design for Wall-Paper, of which the following is a specification.

This invention relates to a new and original design for wall-paper and similar fabrics.

It consists in the novel grouping and configuration of figures hereinafter more fully described.

The accompanying photograph illustrates a face view of wall-paper having my new design.

15 The design consists of the representation of branches and vines with leaves, buds, and flowers thereupon.

A main stem, A, carries a lower branch, C, and upper branches, *a* and *b*. At the right-hand upper portion of the design is shown the end of a branch, *a*. Numerous buds and leaves and the large fully-opened flowers *e f g h*, resembling the flowers of the tulip tree, are found upon the branches *C a b* and on the stem A.

20 A vine, F, runs diagonally across the field of the design and separates into numerous branches and tendrils interlaced with and surrounding the stems and branches *A C a b*, and bearing buds, leaves, and flowers, as shown. Such a vine, E, also appears in the right-hand

lower corner of the design, and a portion of such a vine at the left-hand lower corner. The leaves of the main branches *A C a b* resemble oak-leaves, while those of the vines *E F* 35 are oblong in shape.

The branches and vines, with their leaves, buds, and flowers, extend over the plain background of the paper, so as to cover a large part of it, leaving this background visible through the interstices.

I claim—

1. The design for wall-paper, consisting of the stem A and branches *C, a*, and *b*, with their leaves, substantially as shown. 45

2. The design for wall-paper, consisting of the stem A, branches *C a b*, with the flowers *e f g h* and the buds and leaves, substantially as shown.

3. The design for wall-paper, consisting of the vines *F* and *E*, with the branches, tendrils, buds, leaves, and flowers thereupon, substantially as shown. 50

4. The design for wall-paper, consisting of the stem A, branches *C a b* and their ornamenting leaves and flowers, and of the vines *E F* and their ornamenting leaves and flowers, substantially as shown. 55

EDUARD LEISSNER.
